Primary Examiner — Marissa J Cash*Assistant Examiner* — Kayla Marie Bennett(74) Attorney, Agent, or Firm — Bayramoglu Law Offices LLC(57) CLAIM

The ornamental design for a hanger, as shown and described.

DESCRIPTION

FIG. 1 is a front perspective view of a hanger showing my new design;

FIG. 2 is a front view thereof;

FIG. 3 is a rear view thereof;

FIG. 4 is a right-side view thereof, a left-side view being a mirror image thereof, therefore not shown;

FIG. 5 is a top view thereof;

FIG. 6 is a bottom view thereof; and,

FIG. 7 is a rear perspective view thereof.

The broken lines depict portions of the hanger that form no part of the claimed design.
